UNITED STATES PATENT OFFICE.

BURTIS WILLIAM BENBOW, OF EUREKA, CALIFORNIA.

RECORDING-COMPASS.

1,216,200.

Specification of Letters Patent.

Patented Feb. 13, 1917.

Application filed May 11, 1916. Serial No. 96,899.

To all whom it may concern:

Be it known that I, BURTIS WILLIAM BENBOW, a citizen of the United States, residing at Eureka, in the county of Humboldt and State of California, have invented certain new and useful Improvements in Recording-Compasses; and I do declare the following to be a full, clear, and exact description of the invention, such as will enable others skilled in the art to which it appertains to make and use the same.

My invention which relates broadly to improvements in compasses has for its object to provide a simply constructed yet highly efficient instrument by the use of which the course of any traveling object during a predetermined time or any part of such time may be recorded.

With this general object in view, the invention resides in numerous novel features of construction and in unique combinations of parts to be hereinafter fully described and claimed, the descriptive matter being supplemented by the accompanying drawings which constitute a part of this application and in which:

Figure 1 is a side elevation showing the improved compass in connection with a watch by means of which the recording mechanism is intermittently actuated;

Fig. 2 is a front elevation of the parts shown in Fig. 1 with the watch case in section;

Fig. 3 is a diagrammatic top plan view of the compass proper;

Fig. 4 is a horizontal sectional view through the compass casing showing a top plan view of the magnetic needle and parts in conjunction therewith;

Fig. 5 is a vertical sectional view taken on the plane indicated by the line 5—5 of Fig. 4, the parts being shown in the positions which they normally assume;

Fig. 6 is a similar view showing the arrangement of parts when the mechanism within the watch actuates to dispose the recording means to operative position; and

Figs. 7 and 8 are vertical sectional views taken on the planes indicated by the lines 7—7 and 8—8 of Fig. 4.

In specifically describing the construction shown in the drawings above briefly described, similar characters will be placed on corresponding parts throughout the several views and reference will be herein made to the numerous elements by their respective

indices. To this end, the numeral 1 designates a compass casing having a glass top 2 and a removable bottom 3, the latter being adapted to support thereon any one of a number of compass dials 4 which may be secured against rotation by any preferred means, but which are preferably clamped between said bottom and an internal rib 5 on the casing 1. Rising from the center of the bottom 4 and having a rigid connection therewith is a staff 6 which preferably comprises a lower tubular section 7 and an upper rod-like section 8 telescoping slidably therewith, said section 7 being shown in the present embodiment of the invention as equipped with a stud 9 which depends through the bottom 3 and is upset. It is to be understood, however, that any suitable connection may be provided at this point. The section 8 has secured thereon a suitable stop 10 against which the upper end of a coiled spring 11 bears, the lower end of said spring engaging the bottom 3 as shown. By this arrangement the staff 6 is permitted to contract in length for the purpose of lowering the magnetic compass needle 12 which is mounted thereon.

The needle 12 is preferably provided at its center with an upstanding hollow boss 13 in whose upper end a jewel bearing 14 is secured, said bearing resting substantially without friction on the pointed upper end of the staff section 8. Thus, the compass casing 1 and parts carried thereby may swing freely without having any tendency to move the needle 12.

A slide 15 is mounted on the pointing end 16 of the needle 12, said slide having hinged thereto any suitable marking device 17, a spring 18 being preferably interposed between said slide and marking device to yieldingly retain the latter in contact with the dial 4 when moved into engagement with the latter by depression of the needle 12 in a manner to be described. A toothed bar 19 is secured to the upper end of the slide 15 and extends longitudinally of the needle 12, the teeth of said bar being in mesh with a pinion 20 which is shown in the present embodiment of the invention as mounted on a screw 21 tapped into the boss 13, said pinion being preferably though not necessarily cast integrally with the hub of a ratchet wheel 22 which is also mounted on said screw 21 or upon any suitable stub shaft which might be employed in lieu of said screw. By

means yet to be described, the ratchet wheel 22 is turned a predetermined amount as the needle 12 is successively depressed as above suggested, this movement of said wheel serving to so shift the slide 15 as to move the marking device 17 radially along the dial 4 to mark upon said dial for a purpose to be fully described.

To prevent the slide 15 and marking device 17 from overbalancing the pointing end 16 of the needle 12, a counterbalance 23 is slidably mounted on the other end of said needle, said counterbalance having a toothed adjusting bar 24 similar to bar 19 and 15 meshed with pinion 20 as shown clearly in Figs. 5 and 6, both of said bars being mounted in suitable guides 25 carried by the boss 13. It is to be observed that the teeth of the two bars 19 and 24 mesh with the pinion 20 at diametrically opposite points on the latter and thus both bars will be moved inwardly or outwardly in unison according to the direction in which the ratchet 22 is rotated. It will therefore be obvious that the 25 counterbalance 23 will at all times prevent slide 15 and the marking device 17 from overbalancing the end of the needle upon which they are mounted. Said counterbalance is provided with a depending pin 30 26 which will engage the dial 4 when the needle is moved downwardly, thereby preventing said needle from rocking vertically to such an extent as to prevent the device 17 from properly engaging said dial.

35 A bracket 27 extends laterally from the lower end of the boss 13, said bracket being preferably formed as an integral part of said boss although this construction is not essential. A block 28 is swiveled at 29 to the outer end of said bracket 27 upon a vertical axis, said block being straddled by the connected ends of a pair of dogs 30, which ends are pivoted thereto upon a horizontal axis 30' lying parallel with the needle. The 40 dogs 30 are rigidly joined to each other in any preferred manner but are preferably formed integrally, the free ends of said dogs being positioned adjacent diametrically opposite points on the ratchet wheel 22 and 45 being adapted for engagement one at a time with said wheel, whereby as said dogs are operated successively in a manner to be described, said ratchet wheel will be intermittently turned to move the slide 15 and counterbalance 23 as above stated.

A spring 31 is secured in any preferred manner to the joined ends of the dogs 30, said spring extending above the block 28 and bearing against the periphery of an arbor 32 which is mounted upon a vertical axis, the periphery of said arbor having a notch 33 which receives the end of spring 31 when said arbor is turned from the position shown in Fig. 4 to the opposed position, a suitable 50 handle 34 being provided for so turning said

arbor. When in the position depicted in Fig. 4, the arbor 32 will exert a lateral stress on the spring 31, thus so placing the latter under tension as to turn the block 28 to dispose one of the dogs 30 in operative 70 relation with the ratchet wheel 22, said spring also exerting its tension to rock the dogs downwardly around the pivot 30' to maintain them in normal position, this being possible since the free end of the spring 75 bears under a flange 35 which projects from the periphery of the arbor 32. When the handle 34 is reversed, the spring 31 will continue to exert a downward tension on the dogs 30, but the lateral tension of said 80 spring will be such as to engage the previously idle dog with the ratchet wheel.

A pair of dog operating members preferably in the form of vertical pins 36 are slidably mounted in openings formed 85 through the needle 12 adjacent the boss 13, the upper ends of said pins having heads 37 which underlie the dogs 30 adjacent the free ends of the latter, the lower ends of said pins being normally spaced above the bottom 90 3 as shown in Fig. 5. However, when the needle 12 and all parts carried thereby are depressed as hereinbefore mentioned, the lower ends of the pins 36 will abut the dial 4 which will limit the downward movement 95 of said pins. This will in turn prevent the dogs 30 from further moving downwardly. The result is that as the ratchet wheel 22 continues to move in a downward direction, it will be turned a predetermined amount by 100 the active dog, thereby moving the slide 15 and counterbalance 23 simultaneously in one direction or the other according to the position of the handle 34. This movement of the slide 15 causes the device 17 to mark 105 upon the dial 4 as will be farther on described in detail.

A lever 40 extends through an opening in one side of the casing 1 and is fulcrumed at this point as shown at 41, the inner end of 110 said lever being positioned above the boss 13 and held normally out of contact therewith by a suitable spring 42 which is secured to the casing 1 and bears against the under side of said lever. The outer end of the 115 lever 40 is adapted to be alternately moved upwardly as shown in Fig. 6, the effect being that the inner end of said lever will depress the needle to produce the results heretofore pointed out.

In the present embodiment of the invention, an upright rod 43 bears against the under side of lever 40 at the outer end of the latter, said rod having in its lower end a socket receiving therein a second rod 44 125 which is intermittently raised and lowered by means to be described. The rod 44 is shown in the present embodiment of the device as mounted slidably in a bushing 45 which extends through the edge of a watch 130

casing 46, the inner end of said rod 44 preferably having a head 47 whereby it is prevented from being withdrawn from said bushing. A thrust member 48 preferably in the form of a small metal bar is disposed in rear of the dial of the watch and engages the head 47, suitable guides 49 being provided for the purpose of holding said member 48 in operative position. The lower end 10 of the member 48 has thereon a lateral projection or nose 50 adapted for engagement with the usual intermediate gear wheel 51 of the watch, which wheel serves to retract the member 48 at predetermined intervals 15 against the tension of a spring 52, the tension of the latter being exerted to thrust said member upwardly when released by said wheel. This upward thrust, through the instrumentality of the rods 43 and 44 rocks the 20 lever 40 to depress the needle and its accoutrements.

The spring 52 is fulcrumed between its ends at 53 and one end of said spring is suitably connected with the member 47, it being 25 preferably received in a notch in said member. A slide 54 is mounted within the watch casing 46 and is adapted to be moved into or out of engagement with the other end of said spring to either hold the latter 30 in operative position or to prevent the same from being placed under tension, this construction being very durable and efficient regardless of its simplicity.

Although the same would probably be understood without further explanation, it may be well to state that the intermediate wheel 51 is driven in the usual manner, the numerals 55, 56 and 57 on the drawing (see Fig. 2) representing respectively the usual 40 intermediate pinion, the cannon pinion and the hour wheel.

When operating the improved recording compass from a watch as shown in the drawings, the casing of the latter will preferably 45 be provided with a pair of sockets adjacent its winding stem; said sockets detachably receiving therein studs 58 on the lower ends of legs 59 which are secured to the bottom of the casing 1 in any preferred manner. 50 When the watch is to be detached from the remainder of the instrument, the studs 58 will be removed from their respective sockets and the rod 43 will similarly be detached from 44, a screw cap not shown being now 55 preferably threaded onto the projecting upper end of the bushing 45 to prevent the entrance of dust. It is to be understood, however, that although a watch is shown and described for operating the recording mechanism, any other type of horologe may be 60 provided for the same purpose. However, the specific mechanism described for actuating the lever 40 will preferably be employed regardless of the type of time piece 65 used.

The dial 4 has on its upper surface a plurality of radiating lines 60 representing degrees and has also thereon a number of concentric circles 61 which divide its area into a number of radiating rows of spaces 62 70 which designate hours or fractions of hours according to the size of the dial. In the form illustrated, the spaces run from 6 a. m. to 12 noon and from 1 to 6 p. m., twelve hours in all. The member 48 creates twelve 75 thrusts or impulses upon the lever 40 in one hour. At each one of these thrusts, the needle 12 is depressed to engage the device 17 with the dial 4 and at the same time said device is moyed radially whereupon it will 80 place 12 marks in one hour across the space 62 over which it is being moved. It will thus be evident that as the course of the object upon which the compass is mounted varies, the dial will turn beneath the needle 12, 85 and since during every hour the device 17 places 12 marks on said dial, the course taken will be recorded.

As an example, let us assume that the entire mechanism is fixed rigidly on a ship 90 which at 6 a. m. on a given morning is traveling north northwest and that it maintains this course for four hours. The successive depressions of the needle 12 by its operating mechanism will now cause the device 17 to make 48 distinct marks across the spaces 62 representing the length of time between 95 6 a. m. and 10 a. m. If at this time the course veers to due north, since the needle 12 does not turn, the dial 4 will turn beneath said needle with the ship. The result is that as long as the boat remains on the northerly course, the successive marks made by the device 17 will be disposed on or adjacent the line 60 which represents a northerly direction. In the diagrammatic showing of Fig. 100 3, the course suggested is illustrated and it is assumed that after starting in a true northerly direction, the course has remained unchanged for four hours. Any changes, 105 however, will be recorded upon the dial as will be readily understood. At 6 p. m. the device 17 will have reached the limit of its inward movement whereupon the operator will take out removable bottom and will use 110 new dial, unless he is using a 24 hour dial.

Any dial 4 marked by the member 17 in the manner above described may be kept for use in again passing over the same course and by its use it will be obvious that the 115 computing now necessary will be obviated. Also, the course plotted may be retraced by reversing the dial 4 previously made, and handle 34, causing device 17 to move outwardly across space 62. Furthermore, the 120 dials marked properly by the device 17 may be used as the basis of calculations in order to place courses upon maps and the like.

The operation above described is the same whether the device be mounted upon water 125

craft, air craft, or vehicles and even if it be carried by a person.

The dial 4 is of rather unique arrangement and varies from the usual dial in that the characters E., W., N. E., N. W., S. E. and S. W. designating respectively the directions east, west, northeast, northwest, southeast and southwest are not positioned in the usual manner, but are reversed. In other words, 10 east and west are interchanged, northeast and northwest are interchanged, and southeast and southwest are interchanged. This arrangement has advantages in view of the fact that as the moving object carrying the 15 compass turns for instance to a northwest-
erly direction, the dial 4 will turn with said object and will position N. W. beneath the pointing end 16 of the arrow 12, which end as usual normally points to the north. Similarly, if the object moves from a northerly 20 course and travels westward, the dial 4 will be so moved beneath the needle 12 as to position W. beneath the pointing end of the latter which indicates that a westerly path is 25 being traversed.

From the immediately preceding description, it will be observed that the direction in which the object is moved and the direction indicated by the compass are always 30 identical, this being of great advantage as it obviates all computing to ascertain the direction in which the vessel or the like is progressing.

In the accompanying drawings I have 35 shown certain specific details of construction for illustrative purposes and in the foregoing description, such details have been described, but it is to be understood that within the scope of the invention as claimed, 40 numerous changes may be made without sacrificing the main advantages thereof.

I claim:

1. A recording compass comprising a fixed dial, a compass needle movable there- 45 over, a marking device mounted on said needle for recording a course on the dial, and means for intermittently moving said marking device along the needle.

2. A recording compass comprising a 50 fixed dial, a compass needle movable there- over, a marking device mounted on said needle and normally spaced above the dial, and intermittently operated means for causing 55 said needle to lower and moving the marking device along the same.

3. A recording compass comprising a fixed dial, a compass needle movable there- over, a marking device mounted on said 60 needle and normally spaced above the dial, means for intermittently lowering said 65 needle to engage the marking device with the dial, and means for moving said marking device along the needle when lowered.

4. A recording compass comprising a 65 dial, a compass needle movable thereover, a

marking device mounted on said needle, means for depressing said needle intermittently, and means for moving said marking device along said needle including an operating member adapted to come into contact 70 with and be operated by a fixed part when said needle is depressed.

5. A recording compass comprising a dial, a compass needle movable thereover, a marking device mounted on said needle, means 75 for depressing said needle intermittently, and means for moving said marking device along said needle including an operating pin adapted to come into contact with and be operated by a fixed part when said needle 80 is depressed.

6. A recording compass comprising a fixed dial, a compass needle movable there- over, a marking device mounted on said 85 needle and normally spaced above the dial, means for intermittently lowering said needle to engage the marking device with the dial, and reversible means for moving said marking device along the needle when lowered. 90

7. A recording compass comprising a dial, a compass needle movable thereover, a marking device mounted on said needle for recording a course on said dial, and means for moving said marking device along the 95 needle including a ratchet wheel, a dog engaging the same, and means for success-
ively operating said dog. 90

8. A recording compass comprising a dial, a compass needle movable thereover, a 100 marking device mounted on said needle for recording a course on said dial, and means for moving said marking device along the needle, said means including a ratchet wheel, a pair of dogs for moving said wheel 105 in either direction, and means for successively operating said dogs.

9. A recording compass comprising a dial, a compass needle movable thereover, a marking device mounted on said needle for re- 110 cording a course on said dial, and means for moving said marking device along the needle, said means including a ratchet wheel, a pair of dogs adjacent opposed points on 115 said wheel, means for holding either dog in engagement with said wheel, and means for successively operating said dogs.

10. A recording compass comprising a dial, a compass needle movable thereover, a marking device mounted on said needle for 120 recording a course on said dial, a ratchet wheel mounted on the needle, connecting means between said wheel and marking device for moving the latter along the needle, a pair of rigidly joined dogs mounted on 125 axes at right angles to each other, said dogs being disposed adjacent opposed points on said wheel, a single means for holding either dog in engagement with the wheel and retaining said dog yieldably in inactive posi- 130

tion, and means for intermittently operating the dogs.

11. A recording compass comprising a dial, a compass needle movable thereover, a marking device mounted on said needle for recording a course on said dial, a ratchet wheel mounted on the needle, connecting means between said wheel and marking device for moving the latter along the needle, a pair of rigidly joined dogs mounted on axes at right angles to each other, said dogs being disposed adjacent opposed points on said wheel, a single spring for holding either dog in engagement with the wheel and retaining said dog yieldably in inactive position, a manually rotatable member against which said spring bears, the axis of said member being parallel to one axis of said dogs, said member being adapted to shift said spring to rock the dogs in either direction around the other axis thereof, and means for operating the dogs successively to actuate the ratchet wheel.

12. A recording device comprising a dial, a compass needle movable thereover, a marking device mounted on said needle for recording a course on said dial, a toothed bar secured to said marking device and extending longitudinally of the needle, a pinion in mesh with the teeth of said bar and mounted on said needle, a ratchet wheel for driving said needle, a dog engaging said ratchet wheel, and means for successively operating said dog.

13. A recording device comprising a dial, a compass needle movable thereover, a marking device mounted on one end of said needle for recording a course on said dial, a counterbalance on the opposite end of said needle, and means for moving said marking device and the counterbalance simultaneously along said needle.

14. A recording device comprising a dial, a compass needle movable thereover, a marking device mounted on one end of said needle for recording a course on said dial, a counterbalance on the opposite end of said needle, a pair of toothed bars secured respectively to the marking device and the counterbalance, a pinion in mesh with the teeth of said bars, and means for turning said pinion.

15. A recording compass comprising a dial, a compass needle movable thereover, a marking device mounted on one end of said needle, said device being normally raised above said dial, a counterbalance mounted on the other end of said needle, and intermittently actuated means for causing the needle to lower to engage the marking device with the dial and for simultaneously moving said marking device and counterbalance along the needle.

16. A recording compass comprising a dial, a compass needle movable thereover, a

marking device mounted on one end of said needle, said device being normally raised above said dial, a counterbalance mounted on the other end of said needle, intermittently actuated means for depressing the needle to engage the marking device with the dial, and means for simultaneously moving said marking device and counterbalance along the needle when the latter is lowered.

17. A recording compass comprising a base adapted to support a dial thereon, a telescopic staff rising from said base, yielding means for normally holding said staff extended, a compass needle mounted on said staff, a marking device mounted on said needle and adapted to record a course on the dial, said device being normally spaced above said dial, means for depressing the needle against the tension of the aforesaid yielding means for engaging the marking device with the dial, and means for moving said marking device along the needle when depressed.

18. A recording device comprising a base adapted to support a dial thereon, a telescopic staff rising from said base, a means for normally holding said staff in extended position, a compass needle having a hollow boss into which the upper end of said staff projects, said boss having a bearing resting on said end of the staff, a marking device slidably mounted on one end of said needle and adapted to record a course on the dial, a counterbalance slidably mounted on the other end of said needle, a pair of toothed bars secured respectively to said marking device and counterbalance and extending therefrom into parallel relation, a stub shaft projecting laterally from the aforesaid boss, a pinion mounted on said shaft and meshing with the teeth of both of the aforesaid bars, a ratchet wheel for turning said pinion, a bracket extending laterally from the aforesaid boss in the opposite direction from the stub shaft, a block swiveled on the outer end of said bracket upon an upright axis, a pair of dogs rigidly connected at one end and pivoted to said block upon a horizontal axis, said dogs being disposed adjacent opposed points on the ratchet wheel and being adapted for engagement one at a time with said wheel, means for retaining either of said dogs in operative relation with the wheel, a pair of pins mounted for vertical sliding on the needle and underlying the aforesaid dogs, and means engaging the aforesaid boss for depressing the same and the needle to engage the marking device with the dial, the aforesaid pins being adapted upon this operation to engage said dial and to thus operate the dogs to partially turn the ratchet wheel.

19. In combination, a recording compass, a thrust member for operating the recording means thereof, a spring for thrusting

6
said member in one direction, a projection on said member, and a horologically driven wheel having teeth engaging said projection for successively returning said member 5 against the tension of said spring and releasing it.

20. In combination, a recording compass, a thrust member for operating the recording means thereof intermittently, a spring 10 fulcrumed between its ends and connected at one end with said thrust member, a manually shiftable member to be forced against the other end of said spring to place it under tension for projecting the thrust member, and means for successively returning 15 said thrust member against the tension of said spring and releasing it.

21. An operating mechanism for recording compasses and the like comprising a 20 thrust member, a spring fulcrumed between its ends and connected at one end with said member for projecting the latter, a manually movable member to be forced into contact with the other end of said 25 spring to place the latter under tension, and a horologically driven wheel for successively

retracting said thrust member against the tension of its spring and releasing it.

22. An operating mechanism for recording compasses consisting of a casing adapted to contain a horologe, a rod extending slidably through one side of said casing and extending into its interior, a thrust bar in said casing having a laterally extending nose, a spring fulcrumed between its ends and having one end connected with said bar, a manually operable member to be forced into contact with the other end of said spring to place it under tension, and a toothed wheel in the casing adapted to be 40 driven by the aforesaid horologe, the teeth of said wheel engaging the nose of said thrust bar to successively retract the latter against the tension of the spring.

In testimony whereof I have hereunto set 45 my hand in presence of two subscribing witnesses.

BURTIS WILLIAM BENBOW.
